UNITED STATES PATENT OFFICE

MAX F. BAUR, OF GENEVA, SWITZERLAND, ASSIGNOR TO ISOTHERMOS CORPORATION
OF AMERICA, OF NEW YORK, N. Y., A CORPORATION OF DELAWARE

AUTOMATICALLY-LUBRICATING JOURNAL BOX

Application filed November 8, 1928, Serial No. 317,909, and in Switzerland September 28, 1928.

The invention relates to an improvement in automatically lubricating journal boxes in which the oil contained in a reservoir in the bottom of the box is picked up by radial 5 blades or paddles fixed to the end of the journal and ultimately delivered to the bearing; the object of the invention being to provide means on the upper, inner wall of the box that will be operative to divert oil, 10 which has become viscid because of low temperature and with a consequent tendency to adhere to the inner circumferential wall of the box when carried thereabout by the rotating blades, away from the box wall and 15 onto the bearing.

The invention is illustrated in the accompanying drawings, in which:

Figure 1 is a side elevation, partly in section, of an exemplary journal box for rail- 20 way cars.

Figure 2 is a sectional elevation on line 2—2 of Figure 1.

Referring to the drawings, 1 indicates the body of the box which is usually formed as 25 an integral casting having a seat on the inside of the top wall to receive the bearing 2 which is engaged by the journal 3 on the end of the axle. The front of the box is formed with a circumferentially enlarged chamber 30 4 in the bottom of which is a reservoir or well 5 to contain a body of oil 0 through which the ends of the blade or paddle 10 pass, when the latter, which is fastened to the end 35 of the axle, is rotated by the axle, with the result that oil is picked up by the ends of the blade or paddle and, according to the speed of the latter, either is dropped directly therefrom onto the bearing 2 from above or is thrown against the inner face of the top 40 of chamber 4 by centrifugal force and guided by grooves 6 in the walls of said chamber onto the bearing.

This arrangement effects perfect automatic 45 lubrication of the journal and its bearing so long as the oil is freely fluent, but, when low

temperature conditions cause the oil to thicken and become viscid, the effect of the rotation of the distributing blade or paddle 10, especially when the speed of rotation is high, is to draw the oil in a mass about the inner circumferential wall of chamber 4 in the form of a solid ring, the cohesive and adhesive effects of which are sufficient to overcome the force of gravity, so that no oil reaches the bearing 2. 50 In order to overcome this difficulty, means are provided in the upper part of the chamber 4 to break up and divert this rotating ring of oil toward the bearing, so that gravity may be effective to direct the viscid oil onto the top 55 of the bearing 2.

An effective means to this end is in the form of an inwardly extending barrier or abutment, such as a taper faced rib 7 extending transversely of the highest portion of the inner wall of chamber 4, against which the moving 60 sheet of viscid oil impinges and is thereby turned or diverted downward, as shown in Figure 2, so that the force of gravity will direct the mass onto the bearing 2.

Obviously the abutment aforesaid may be 65 of various structural forms and may be varied as to size and the extent of its projection toward the bearing, but the preferred form is that of a tapered rib located midway of the 70 series of grooves 6 in the top of chamber 4 and extending transversely of the chamber, which 75 serve to direct the oil onto the bearing under normal conditions.

What I claim is:

1. A journal box including in combination with the axle having a lubricant distributing member thereon, a plurality of lubricant guiding and directing ribs formed at the top inner face of the box above the path of the distributing member, and a lubricant precipitating member arranged at the middle portion of said ribs thereby to direct lubricant onto the bearing.

2. In a journal box, the combination of an 85 axle having a lubricant distributing member 90

thereon, and means for directing lubricant onto the bearing, said means comprising an inclined top wall of the box having a plurality of lubricant guiding and directing ribs formed thereon, and a lubricant precipitating rib having a horizontal dripping edge extending across the top of the box and located in the path of lubricant thrown from said lubricant distributing member.

10 In testimony whereof I have signed my name to this specification.

MAX F. BAUR.
